(57) **CLAIM**

The ornamental design for a inflator and deflator air compressor, as shown.

DESCRIPTION

FIG. 1 is a perspective view of a inflator and deflator air compressor showing my new design:

FIG. 2 is a front side elevational view thereof;

FIG. 3 is a rear side elevational view thereof;

FIG. 4 is a left view thereof;

FIG. 5 is a right view thereof;

FIG. 6 is a top plan view thereof; and,

FIG. 7 is a bottom plan view thereof.
